UNITED STATES PATENT OFFICE.

WALTER CHIPPERFIELD, OF ROMFORD, ENGLAND, ASSIGNOR TO RONEO LIMITED, OF LONDON, ENGLAND, A COMPANY OF GREAT BRITAIN.

MEANS FOR SIMULTANEOUSLY LOCKING SLIDING DRAWERS, SHELVES, OR OTHER SLIDING STRUCTURES.

1,353,453.

Specification of Letters Patent. Patented Sept. 21, 1920.

Application filed January 5, 1920. Serial No. 349,589.

To all whom it may concern:

Be it known that I, WALTER CHIPPERFIELD, a subject of the King of Great Britain, residing at Roneo Works, Romford, in the county of Essex, England, Great Britain, have invented new and useful Improvements in or Relating to Means for Simultaneously Locking Sliding Drawers, Shelves, or other Sliding Structures, of which the following is a specification.

This invention relates to improvements in or relating to means for simultaneously locking sliding drawers, shelves, or other sliding structures, and has for its object to so construct locking mechanism whereby when all the drawers of a series are properly closed and the lock actuating rod is pushed home, all the drawers will be simultaneously locked, but should one or more of the said drawers be placed in a nearly closed position, the locking mechanism when actuated will complete the closure of such nearly closed drawer or drawers and the whole of the series will then be simultaneously locked. Further if any one of the series of drawers is left open to such an extent that it does not become automatically closed by the action of the locking mechanism, such a drawer upon being pushed into its closed position will thereupon become locked without bringing about or causing any motion of the locking rods themselves.

The invention is moreover directed to providing a locking device which is little if at all affected by friction, and which is not liable to jam, and also in which the strength of the springs employed can be materially reduced, as compared with previous constructions.

The invention will be fully described with reference to the accompanying drawings, whereon, Figure 1. shows in vertical section so much of a case containing a sliding drawer as is necessary to describe the locking mechanism shown applied thereto according to this invention, the drawer being shown locked. Fig. 2. is a sectional plan view of the locking mechanism corresponding to Fig. 1. Fig. 3. is a sectional elevation showing the locking devices in the unlocked position. Fig. 4. is a similar view showing the locking mechanism in the act of effecting the closure of a drawer which has been

left very nearly closed, and Fig. 5. is a similar view showing a drawer which has been left open in the act of being pushed into its closed and locked position.

Referring to the drawings, each drawer 1, is fitted beneath its base and at its rear end with a locking arm 2 pivoted at 3 to a bracket 4 fixed to the base of the drawer, the free end of the arm 2 extending to or toward the rear end 1^x of the drawer 1, and the arm 2 is normally held up toward or in contact with the base of the drawer by a light spring 5.

The rear end of the arm 2 is formed with a cam shaped member comprising a rear vertical face 6, from the upper edge of which there proceeds an upper rearwardly and downwardly inclined lip 7, and from the lower edge there proceeds a lower rearwardly and downwardly inclined lip 8. The cam shaped member extends laterally from and at right angles to the length of the locking arm 2, and the axis of the pivot 3 extends at right angles to the direction of motion of the sliding drawer.

At the rear of the sliding drawers 1 and carried by suitable guides on the interior surface of the back of the case, is a locking rod 9 capable of receiving vertical sliding motions, and for each drawer the locking rod 9 carries a roller 10. Each roller 10 is revolvably carried on a pivot pin, which latter is supported by a bracket 11, see Figs. 2 and 5, in a suitable manner at a proper distance from the locking rod 9. The location of the rollers 10, when the drawers are closed and unlocked is such as shown at Fig. 3. and the peripheries of said rollers are at a lower level than the lower edges of the cam members carried by or formed upon the locking arms 2. When a drawer so fitted is completely closed, see Fig. 3. the plane of the forward vertical face 6 of the cam member of the locking arm 2 is at the rear of the roller 10 carried by the vertical locking rod 9 and is tangential with its periphery.

It will now be understood that when the vertical locking rod 9 is given an upward vertical movement, the rollers 10, in accompanying such movement, will pass respectively in front of the cam member of the locking arms 2, and the peripheries of the rollers will contact with the forward vertical faces 6 of the cam members and thereby

all the drawers will be locked. Moreover it is also to be observed that the rollers 10 in engaging the cam members will turn about their axis and the locking motion is thus effected with the minimum of friction, which is an important consideration in this manufacture.

Should one or more of the drawers be nearly but not completely closed as shown 10 at Fig. 4, its locking rollers 10, by the upward motion of the locking rod 9 will be brought to act upon the under surfaces of the lower rearwardly inclined lip 8 of the cam member of the locking arm 2, and 15 whereby the drawer will be caused to complete its closure as the roller 10 passes up the inclined lip 8 of the cam member, and the drawer will be locked when the roller 10 has completed its upward movement and 20 stands in front of the vertical face 6 of the cam member.

Should the drawer not be sufficiently closed to permit such automatic closure to be effected during the operation of the locking devices, then obviously the locking roller 10 of each drawer 1 would pass upward into locking position at the rear of the cam member of the locking arm 2, and the drawer would be neither closed nor locked. In such 25 a case upon the drawer being pushed home, the upper lip 7 of the cam member of the locking arm 2 would strike the roller 10 as at Fig. 5, with the result that the locking arm 2 would receive a downward angular 30 motion about its pivot 3 and the upper edge of the cam member of the arm 2 would pass beneath the roller 10 and the cam member would then rise rearward of the roller, owing to the arm moving about its pivot under 35 the action of its spring; thus the drawer would become locked without any movement of the vertical locking rod 9 taking place.

The invention is not limited to the particular means by which the vertical locking rod is brought to and held in its locking position by operating devices actuated from the exterior of the case, but such may conveniently consist, as shown at Fig. 1, of a

horizontal sliding rod 11* in the upper part 50 of the casing 12, one end of which horizontal rod 11* extends to the exterior of the case, while the other end is connected to one arm of a two armed lever 13 the other arm of which operates the vertical locking rod 9. 55

Having thus described my invention what I desire to secure by Letters Patent of the United States is as follows:—

1. Means for locking sliding drawers, shelves, and other sliding structures comprising a vertically movable locking rod, a roller or equivalent thereon for each drawer or the like to be locked, and means operable from the exterior of the case for raising and holding said rod in its locking position, in 60 combination with a pivoted locking arm on each drawer extending rearwardly and about horizontally in the direction of motion of said drawer, its free rear end being capable of motion in one (say a downward) 65 direction against spring action, and a cam shaped member carried on the rear end of said arm such that when said locking arm is raised a roller carried thereby passes in front of said cam member and locks said 70 drawer, and when said drawer is very nearly closed the locking roller acts on a surface of said cam member, closes the drawer, and effects its locking action, while should said drawer be pushed home after the rod has 75 been raised to the locking position, said cam member contacts with said roller, the locking arm is raised, and said cam member passes beneath and behind the roller and effects the locking action.

2. Means for locking sliding drawers, comprising a bracket secured to the base of each drawer, a spring-controlled locking arm pivoted to said bracket, the free end of said arm forming a cam member comprising a plurality of cam surfaces, a vertically movable rod, a bracket secured to said rod, and a roller carried by said bracket for engaging said cam surfaces.

In testimony whereof I have signed my 95 name to this specification.

WALTER CHIPPERFIELD.
